Primary Examiner — Rosemary K Tarcza(74) *Attorney, Agent, or Firm* — Oblon, McClelland, Maier & Neustadt, L.L.P.(57) **CLAIM**

The ornamental design for charging units, as shown and described.

DESCRIPTION

FIG. 1 is a perspective view of a charging unit showing the front, top, and right side of my new design in a closed position as viewed from the right side of the page;

FIG. 2 is a side elevational view of one side thereof;

FIG. 3 is a side elevational view of the opposite side thereof;

FIG. 4 is a rear elevational view thereof;

FIG. 5 is a front elevational view thereof;

FIG. 6 is a top elevational view thereof; and,

FIG. 7 is a bottom elevational view thereof.

1 Claim, 5 Drawing Sheets(56)
